UNITED STATES PATENT OFFICE.

EDWIN NORTON, OF NEW YORK, N. Y., ASSIGNOR TO AUTOMATIC VACUUM CANNING COMPANY, OF CHICAGO, ILLINOIS, A CORPORATION OF ILLINOIS.

AUTOMATIC VACUUMIZING AND DOUBLE-SEAMING MACHINE.

SPECIFICATION forming part of Letters Patent No. 762,551, dated June 14, 1904.

Application filed August 7, 1903. Serial No. 168,561. (No model.)

To all whom it may concern:

Be it known that I, EDWIN NORTON, a citizen of the United States, residing in New York, in the county of New York and State of New York, have invented a new and useful Improvement in Automatic Vacuumizing and Double-Seaming Machines, of which the following is a specification.

My invention relates to machines for vacuumizing or exhausting the air from cans and seaming the covers thereon.

The object of my invention is to provide an automatic machine of a simple, efficient, and durable construction by means of which sheet-metal cans may be automatically, rapidly, and cheaply vacuumized, hermetically sealed, and the covers thereof double-seamed thereon.

My invention consists in the means I employ to practically accomplish this object or result—that is to say, it consists, in connection with a continuously-moving carrier having a plurality of vertically-reciprocating can-seats thereon, each adapted to receive and support a single can or vessel, and a plurality of receivers mounted on the carrier open at their lower ends and adapted to be closed by the vertically-reciprocating can-seats, of an exhaust mechanism, means for automatically opening and closing the exhaust to each receiver as the carrier moves, a double-seaming head inside each receiver having a plurality of successively-operating double-seaming rollers, means for automatically feeding or delivering the cans one by one upon the can-seats of the carrier, means for automatically discharging the cans therefrom after they have been vacuumized and the covers double-seamed thereon, means for vertically reciprocating the can-seats, and means for operating the other parts in proper succession to first close the can-seat against the receiver and move the can within the receiver, exhaust the air therefrom and from the can therein, then force the seaming-head down upon the cover of the can to compress the packing interposed between the can and its cover, and thus hermetically seal the can *in vacuo* or while the vacuum is maintained in the receiver, then admit air to the

receiver and open the same by withdrawing the vertically - reciprocating can - seat therefrom, the seaming-head following the can-seat down, and thus holding the vacuumized can clamped between the seaming-head and the can-seat, and then finally operating the seaming-rollers to double-seam the cover on the vacuumized can, the seaming operation being performed while the can is separated from the receiver, so that the seaming operation can be inspected. The vacuumized and double-seamed can is then automatically discharged from the machine.

My invention also consists in the novel construction of parts and devices and in the novel combinations of parts and devices herein shown or described.

In the accompanying drawings, forming a part of this specification, Figure 1 is a plan view of an automatic combined vacuumizing and double-seaming machine embodying my invention. Fig. 2 is a central vertical longitudinal section. Fig. 3 is a horizontal section on the broken line 3 3 of Fig. 2. Fig. 4 is a horizontal section on line 4 4 of Fig. 2. Fig. 5 is a detail elevation of the can-feed mechanism. Fig. 6 is a detail section on line 6 6 of Fig. 2. Fig. 7 is an enlarged detail central vertical section through one of the receivers. Figs. 8 and 9 are enlarged detail central vertical sections of one of the double-seaming heads, showing the seaming-rollers in different positions. Fig. 10 is a horizontal section on line 10 10 of Fig. 8. Figs. 11 and 12 are detail sectional views before and after the seaming operation.

In the drawings like letters of reference indicate like parts throughout all the figures.

In said drawings, A represents the frame of the machine.

B is a continuously-moving carrier, preferably a rotatory turret or wheel, furnished with a plurality of vertical reciprocating can-seats b, having registering pins or devices b' for registering the cans with the chucking or clamping disks d of the seaming-heads D, which are likewise mounted on the carrier above the can-seats b and which reciprocate

vertically with the can-seats after the cans are clamped between the can-seats and the seaming-heads.

C are a plurality of vacuum-receivers, 5 each preferably bell-shaped or open at its lower end and mounted on the rotatable carrier B. Each of the receivers C is furnished at its lower end with an elastic or rubber packing e to close and seal the receiver tightly against 10 the can-seats b of the carrier B. When the vertically - reciprocating can - seat b is in its lowermost position, its upper face is flush with the upper face of the horizontal plate B' of the carrier B, said plate B' having a series of 15 recesses b³ to receive the can-seats b. Each of the can-seats b is preferably furnished with an inserted thin disk of rubber b² to compensate for inequalities in the heights of the cans. The receivers C are rigidly but preferably 20 removably connected to an upright drum or shell B⁵ of the carrier B by brackets B², furnished with connecting-bolts. Each of the receivers C is furnished with a stuffing-box C³, through which the operating-shaft D' of the 25 seaming-head D extends.

The vertically-reciprocating can-seats b are vertically reciprocated or operated, as required, to first move the can-seat upward and move the can within the receiver and close 30 the lower end of the receiver and then, after the air has been exhausted from the receiver and can and the clamp-disk d of the seaming-head D moved down to clamp the cover on the can, to move downward with the seaming-head 35 to separate the can and seaming-head from the receiver and to bring the can-seat b again flush with the plate B' of the carrier B, so that the can can be discharged automatically after the seaming operation is completed by 40 means of a stationary cam or sinuous track A' on the frame of the machine, which engages a stem b⁴ of the can-seat b. The stem b⁴ is preferably provided with an antifriction-roller b⁵ to travel on the cam or track A'.

45 Leading into each of the receivers C is an exhaust-pipe E, communicating with an exhaust device E' through pipe E² to the valves F, which control the communication. The valve-shells F' of the valves F have each an exhaust-port f and an inlet-port f', through 50 which latter air may be admitted to the receiver to break the vacuum after the cover has been seated on the can or vessel by operation of the clamping-disk d of the seaming-head D in each receiver. Corresponding ports in the valves F communicate with the ports f, f' in the valve-shells F'. The valve-shells F' are mounted on the carrier B. The frame A has a central standard or shaft A³, 55 forming or having a bearing A⁴ for the journals or hub B³ B⁴ of the carrier B and provided with stuffing - box connections a² a³ with said carrier. The exhaust-pipe E², leading 60 to the exhaust device E', communicates through a channel a³ in the sleeve or bear-

ing A⁴ with a chamber a⁴, which has a communication b¹¹ through the hub B⁴ with a chamber b²² in said hub B⁴, into which lead the exhaust-pipes E, which extend to each of the receivers and in which pipes E the valves F and valve-shells F' are inserted. The valves F are automatically operated or reciprocated as the carrier B rotates preferably by a stationary cam F², secured to a stationary upright shaft or post A³, which cam the valve-stems F⁴ engage as the carrier B rotates. A spring F⁵ on each of the valve-stems moves the valve-stem in the opposite direction. The seaming-head D inside each of the receivers C is furnished with a cam-clamping chuck or disk d, having a countersink or shoulder d' to fit the countersink of the cam-head x and co-operate with the double-seaming roller d² d³ d⁴. Each of the double-seaming rollers is carried on an operating-lever d⁵, pivoted to 70 lugs or ears d⁶ on the seaming-head D and operated by cams d⁸ d⁹ d¹⁰ d¹¹ on the vertically-reciprocating slides D², with which each of the seaming-heads D is provided. The cams d⁸ d⁹ d¹⁰ are differently located on the 75 slide D², so as to successively operate the set of double-seaming rollers—that is to say, as the slide D², carrying these cams, is depressed the first causes the first double-seaming roller d² to engage the flange of the can-head and 80 curl or fold the same partially around the seaming-flange on the can-body and then operates the next seaming-roller d³, which serves to further fold the seaming-flanges downward and together and then operates the pair of 85 finishing-rollers d⁴, which are alike and preferably should be operated simultaneously and serve to finish the seam and press the folds thereof tightly together. The can-clamping 90 chuck or disk d has antifriction or ball bearing connections d¹¹ d¹² d¹³ with the seaming-head D, so that the chuck-disk d and the can 95 may remain stationary or non-rotating, while the seaming-head D rotates around it.

The seaming-head D has a spring connection D⁵ with the cam-slide D², which latter cam-slide is directly secured to the rotating and reciprocating operating-shaft D' of the seaming-head. This interposed spring D⁵ between the seaming-head and cam-slide causes 100 the seaming-head D or the clamping-disk d, carried thereby, to first clamp and press the cover x of the can X down upon the can after the air has been exhausted therefrom and from the receiver and to hold the cover thus sealed to the can while the vacuum in the receiver is being broken and the receiver opened and while the can is being withdrawn therefrom by the downward reciprocating movement of the can-seat b, during which time the 105 seaming-head D and its clamp-disk d move downward with the can-seat b and while the cam-slide D², by its further downward movement, operates the seaming - rollers as required. The interposed spring D⁵ permits 110

the necessary further downward movement of the cam-slide to effect the seaming operation.

The seaming-head is preferably provided with a can-stripper or ejector-disk d^{14} , having an operating - stem d^{15} , which extends up through the operating-shaft D' of the seaming-head and through the guide-stud d^{16} , with which the clamp-disk d is provided. Springs d^{17} , attached to the upper ends of the seaming-roller levers d^8 and connecting the same, serve to retract the seaming-rollers. The required up-and-down or reciprocating movement is communicated to the seaming-head shafts D' as the carrier B rotates by a stationary cam D^4 , secured to the stationary shaft or post A^3 of the frame and operating through connecting - levers D^5 , having antifriction-rollers D^6 to engage the cam and forks D^7 , connected to the shaft D' by adjustable collars D^8 D^9 . The ejector-stem d^{15} on each of the seaming-heads is operated in one direction by a stationary cam D^{10} , supported on the frame A , each of the stems d^{15} having a spring d^{18} to move the same in the opposite direction. The spring d^{18} surrounds the ejector-stem d^{15} , and its lower end bears against the end of the seaming-head shaft D' , and thus tends to hold the ejector in its retracted position, except 30 when the ejector-stem is depressed by the stationary cam D^{10} .

The required rotatory movement is communicated to each of the seaming-heads D or its operating-shaft D' as the carrier B rotates, 35 preferably by means of a spur-gear D^{11} , one on each of said shafts D' , engaging a rotating spur-gear D^{12} , which is journaled on the frame of the machine and which is provided with a bevel - gear face D^{13} , that meshes with the bevel-gear D^{14} on shaft D^{15} , carrying a driving-pulley D^{16} . The carrier B is provided with a shell or drum B^5 to give proper support to the various operating-levers and parts carried thereby, and this carrier is rotated 40 preferably continuously by a gear B^6 thereon, which engages a worm B^7 on a driving-shaft B^8 . The cans are automatically fed or delivered onto the can-seats b of the carrier B , the upper surface of which seats at this time 45 are flush with the upper surface of the carrier-plate B' from the conveyer-belt K by a movable feeder H , having a series of can-pusher arms h , which engage the cans one by one and move them along a curved guideway H' onto 50 the carrier B against the registering devices or pins b' of the can-seats. The feeder H is preferably given a rotatory movement in coöperation with the continuously-rotating carrier B by means of operating-arms h' on the 55 feeder, which engage the pins or projections b' on the carrier B .

As the carrier B rotates the cans are automatically discharged one by one therefrom by a can-discharging arm M , projecting in the 60 path of the cans, the same operating in con-

junction with a guide M' to deliver the cans upon the can-discharging feeder or belt N , which travels upon a suitable pulley N' . At the time the can is discharged from the can-seat b by the discharging-arm M the vertically- reciprocating can-seat b is again flush with the carrier-plate B' . The can-feed conveyer or belt K travels upon a pulley K' and a plate H^2 , flush or on a level with the conveyer-belt K , and carrier B supports the cans as they are moved by the feeder H from the conveyer K onto the carrier B . A similar plate M^2 , flush with the discharge-conveyer N and carrier B , bridges the space between the carrier and the conveyer N . The can-conveyers N and K are 75 continuously driven from any suitable series of power.

The operation is as follows: The cans X on the feed-conveyer K , having each its cover x loosely in place thereon, are continuously 80 crowded against the guide H' at the end of said conveyer, so that one of the cans is always in position to be engaged by one of the feeder-arms h as the feeder H rotates, and thus be carried by the feeder-arm onto the 85 carrier B and against the registering pins or devices b' of the can-seat b , which at this time is flush with the carrier-plate B' , the seaming-head D being at this time in its lifted or raised position inside the receiver C . As the carrier B continues its rotation the vertically- 90 movable can-seat b by its operating-cam A' is reciprocated or moved upward against the lower end of the receiver C , thus closing the receiver and moving the can into the receiver, 95 and then the valve F in the exhaust-pipe is moved by its operating-cam F^2 to open the communication between the receiver C and the exhaust device E' through the intermediate communicating pipes or passages. The 100 exhaust communication with the receiver remains open for a portion of the revolution of the carrier, thus exhausting the air from the receiver and from the can and its contents, the cover x during this time remaining loosely, 105 in place on the can or vessel X . After the air has thus been exhausted from the can and its contents the seaming - head D , with its can-clamping disk d , is next forced down by its operating-cam D^4 , thus seating the cover x firmly and evenly on the can X and compressing the packing x' between the seaming-flanges x^2 x^3 of the can and cover and holding the same thus compressed until after the double-seaming operation is completed. The controlling-valve F is next again moved by its operating-cam, thus breaking the vacuum and admitting air to the receiver, and then the vertical reciprocating can-seat b and seaming-head D are together reciprocated or moved 115 downward, thus withdrawing the can from the receiver while holding the cover firmly clamped on the now vacuumized can. After the can has thus been withdrawn from the receiver the seaming-head shaft D' is by its op- 120

erating - cam D⁴ given a further downward movement, thus still further moving the cam-slide D², and thus compressing the interposed spring D³ and successively operating the double-seaming rollers and forcing them into engagement with the seaming-flanges of the can and cover, and thereby double-seaming the cover on the can, the seaming-head D rotating continuously through its connecting-gearing. As the carrier B continues its rotation the vacuumized sealed and double-seamed can is discharged from the carrier B by the can-discharging arm M and delivered upon the discharge-conveyer N.

15 The operation thus described in respect to one can, one can-seat, one receiver, and one seaming-head simultaneously takes place for the others, so that a continuous stream or series of cans passes into, through, and off of the machine and this continuously without stop or interruption. By this means the cans or vessels may be vacuumized and their covers hermetically sealed and double-seamed thereon very rapidly and cheaply and also perfectly, 20 as the can and the cover and the double-seaming rollers are open to inspection during the double-seaming operation, as the can-seat, can, and seaming-head are withdrawn from within the receivers during this operation.

25 30 I claim--

1. In a machine for vacuumizing and seaming covers on cans or vessels, the combination with a horizontal traveling carrier having a plurality of vertically-reciprocating can-seats, 35 of a plurality of receivers mounted on the carrier, and having open lower ends adapted to be closed by said can-seats and a plurality of seaming-heads, one inside each receiver, and mechanism for automatically reciprocating the can-seats as the carrier travels, said receivers being normally open and being closed and opened by the reciprocation of the can-seats, substantially as specified.

2. In a machine for vacuumizing and seaming covers on cans or vessels, the combination with a carrier having a plurality of vertically-reciprocating can-seats, of a plurality of receivers mounted on the carrier, and having open lower ends adapted to be closed by said 45 can-seats and a plurality of seaming-heads, one inside each receiver, and a feeder for automatically delivering the cans upon the can-seats of the carrier, substantially as specified.

3. In a machine for vacuumizing and seaming covers on cans or vessels, the combination with a carrier having a plurality of vertically-reciprocating can-seats, of a plurality of receivers mounted on the carrier, and having open lower ends adapted to be closed by said 55 can-seats and a plurality of seaming-heads, one inside each receiver, and a feeder for automatically delivering the cans upon the can-seats of the carrier, and a conveyer for delivering the cans to the feeder, substantially as specified.

4. In a machine for vacuumizing and seaming covers on cans or vessels, the combination with a carrier having a plurality of vertically-reciprocating can-seats, of a plurality of receivers mounted on the carrier, and having open lower ends adapted to be closed by said can-seats and a plurality of seaming-heads, one inside each receiver, and a feeder for automatically delivering the cans upon the can-seats of the carrier, and a conveyer for delivering the cans to the feeder, and a device for automatically discharging the cans from the carrier, substantially as specified. 75

5. In a machine for vacuumizing and seaming covers on cans or vessels, the combination with a carrier having a plurality of reciprocating can-seats, of a plurality of receivers mounted on the carrier, having open lower ends adapted to be closed by said can-seats, and a plurality of double-seaming heads, one inside each receiver, substantially as specified. 80

6. In a machine for vacuumizing and seaming covers on cans or vessels, the combination with a carrier having a plurality of reciprocating can-seats, of a plurality of receivers mounted on the carrier, having open lower ends adapted to be closed by said can-seats, and a plurality of double-seaming rollers, one inside each receiver, and a feeder for automatically delivering the cans upon the carrier, 90 and a device for automatically discharging the cans from the carrier, substantially as specified. 95

7. In a machine for vacuumizing and seaming covers on cans or vessels, the combination with a carrier having a plurality of reciprocating can-seats, of a plurality of receivers mounted on the carrier, a plurality of seaming-heads one inside each receiver, and mechanism for operating said parts, to first close the can-seat against the receiver, then exhaust the air from the receiver and the can therein, then force the seaming-head down on the can, then withdraw the seaming-head, can-seat and can from the receiver and then actuate the seaming-rollers of the seaming-head, substantially as specified. 100 105

8. In a machine for vacuumizing and seaming covers on cans or vessels, the combination with a carrier having a plurality of reciprocating can-seats, of a plurality of receivers mounted on the carrier, each having an open lower end, a plurality of double-seaming heads, one inside each receiver, and each having a set of double-seaming rollers and mechanism for operating said parts, to first close the can-seat against the receiver, then exhaust the air therefrom, then force the can-cover down on the can, then withdraw the seaming-head, can and can-seat from the receiver, and then actuate the double-seaming rollers of the seaming-head, substantially as specified. 115 120

9. The combination with a continuously-rotating carrier, having a plurality of reciprocating can-seats thereon, of a plurality of op- 125 130

- posing can-clamping disks, a plurality of rotating seaming-heads having seaming-rollers, a plurality of receivers surrounding the seaming-heads, and means for automatically reciprocating the can-seats on the carrier as the carrier rotates, said receivers being normally open and being closed and opened by the reciprocation of the can-seats, substantially as specified.
10. The combination with a rotating carrier, having a plurality of reciprocating can-seats thereon, of a plurality of opposing can-clamping disks, a plurality of rotating seaming-heads having seaming-rollers, a plurality of cam-slides for operating the seaming-rollers, and a plurality of receivers surrounding the seaming-heads, substantially as specified.
11. The combination with a rotating carrier, having a plurality of reciprocating can-seats thereon, of a plurality of opposing can-clamping disks, a plurality of rotating seaming-heads having seaming-rollers, a plurality of cam-slides for operating the seaming-rollers, a plurality of receivers surrounding the seaming-heads, and a feeder for automatically delivering the cans to the carrier, substantially as specified.
12. The combination with a rotating carrier, having a plurality of reciprocating can-seats thereon, of a plurality of opposing can-clamping disks, a plurality of rotating seaming-heads having seaming-rollers, a plurality of cam-slides for operating the seaming-rollers, a plurality of receivers surrounding the seaming-heads, a feeder for automatically delivering the cans to the carrier, and a device for automatically discharging the cans from the carrier.
13. The combination of a vertically-reciprocating can-seat with a receiver and a double-seaming head inside the receiver, said double-seaming head having a plurality of seaming-rollers, operating-levers therefor, and a cam-slide for actuating the operating-levers of the seaming-rollers, substantially as specified.
14. The combination with a reciprocating, non-rotating can-seat, of a seaming-head having a can-clasping disk and a plurality of seaming-rollers, a plurality of operating-levers therefor, and a cam-slide for actuating the operating-levers of the seaming-rollers and a receiver having an open lower end adapted to be closed by said reciprocating can-seat, substantially as specified.
15. The combination with a double seaming-head, having a plurality of seaming-rollers, and operating-levers therefor, pivoted to said head, and a cam-slide for actuating said operating-levers of the seaming-rollers, a receiver surrounding and inclosing said seaming-head, and having an open lower end and a reciprocating can-seat for closing the open lower end of the receiver and moving the can into the same, substantially as specified.
16. The combination with a carrier having a plurality of reciprocating can-seats, of a plurality of receivers having open lower ends closed by said reciprocating can-seats for consecutively and simultaneously exhausting the air from a plurality of cans and a plurality of seaming-heads inside the receivers for consecutively and simultaneously seaming a plurality of cans, substantially as specified.
17. The combination with a carrier having a plurality of reciprocating can-seats, of a plurality of receivers having open lower ends closed by said reciprocating can-seats for consecutively and simultaneously exhausting the air from a plurality of cans and a plurality of seaming-heads inside the receivers for consecutively and simultaneously seaming a plurality of cans, and a feeder for automatically delivering the cans to the carrier, substantially as specified.
18. The combination with a carrier having a plurality of reciprocating can-seats, of a plurality of receivers having open lower ends closed by said reciprocating can-seats for consecutively and simultaneously exhausting the air from a plurality of cans and a plurality of seaming-heads inside the receivers for consecutively and simultaneously seaming a plurality of cans, and a discharge device for automatically delivering the cans from the carrier, substantially as specified.
19. The combination with the horizontally-moving carrier having a vertically-reciprocating can-seat, adapted to close the lower end of the receiver, of a receiver mounted on the carrier and having an open lower end and a seaming mechanism inside the receiver, and mechanism for automatically reciprocating the can-seat on the carrier as the carrier moves, said receiver being normally open and being closed and opened by the reciprocation of the can-seat, substantially as specified.
20. The combination with a horizontally-moving carrier having a vertically-reciprocating can-seat, of a receiver having an open lower end, a roller seaming-head inside the receiver, having a can-clamping disk for seating the cover on the can and clamping the can and cover together, an exhaust mechanism, a valve for controlling the admission of air to the receiver, and mechanism for automatically reciprocating the can-seat on the carrier as the carrier moves, said receiver being normally open and being closed and opened by the reciprocation of the can-seat, substantially as specified.
21. The combination with a horizontally-moving carrier having a plurality of reciprocating can-seats, of a plurality of open-ended receivers, a plurality of seaming-heads inside the receivers, furnished each with a can-clamping disk and with a plurality of successively-operating double-seaming rollers, and mechanism for automatically reciprocating the can-seats on the carrier as the carrier moves, said receivers being normally open and being

closed and opened by the reciprocation of the can-seats, substantially as specified.

22. The combination with a carrier having a plurality of reciprocating can-seats, of a plurality of open-ended receivers and a plurality of seaming-heads inside the receivers, furnished each with a can-clamping disk and with a plurality of successively-operating double-seaming rollers, an exhaust mechanism and a plurality of valves for controlling the exhaust and admission of air to the receivers, substantially as specified.

23. The combination with a rotating carrier having a plurality of reciprocating can-seats thereon, of a plurality of opposing can-clamping disks, a plurality of rotating seaming-heads having seaming-rollers, a plurality of receivers surrounding the seaming-heads, and stationary cams for operating the reciprocating can-seats and seaming-heads as the carrier rotates, substantially as specified.

24. The combination with a rotating carrier having a plurality of reciprocating can-seats thereon, of a plurality of opposing can-clamping disks, a plurality of rotating seaming-heads having seaming-rollers, a plurality of receivers surrounding the seaming-heads and exhaust mechanism, a plurality of valves for controlling the exhaust and admission of air to the receivers, and stationary cams for operating the reciprocating can-seats, seaming-heads and valves as the carrier rotates, substantially as specified.

25. In a machine for vacuumizing and seaming covers on cans or vessels, the combination with a carrier having a plurality of reciprocating can-seats, of a plurality of receivers mounted on the carrier and having open lower ends, a plurality of seaming-heads, one inside each receiver and a stationary cam for operating the reciprocating can-seats, substantially as specified.

26. In a machine for vacuumizing and seaming covers on cans or vessels, the combination with a carrier having a plurality of reciprocating can-seats, of a plurality of receivers mounted on the carrier and having open lower ends,

a plurality of seaming-heads, one inside each receiver, a stationary cam for operating the reciprocating can-seats, and a stationary cam 50 for operating the seaming-heads, substantially as specified.

27. In a machine for vacuumizing and seaming covers on cans or vessels, the combination with a carrier having a plurality of reciprocating can-seats, of a plurality of receivers mounted on the carrier and having open lower ends, a plurality of seaming-heads, one inside each receiver and a stationary cam for operating the reciprocating can-seats and a can-feeder, 60 substantially as specified.

28. The combination with a carrier having a plurality of reciprocating can-seats, of a plurality of open-ended receivers, a plurality of seaming-heads inside the receivers, furnished each with a can-clamping disk, a plurality of successively-operating double-seaming rollers, a plurality of cam-slides, one for each seaming-head and a spring or yielding connection between each cam-slide and its 70 seaming-head, substantially as specified.

29. The combination with a carrier having a plurality of reciprocating can-seats, of a plurality of open-ended receivers, a plurality of seaming-heads inside the receivers, furnished each with a can-clamping disk, a plurality of successively-operating double-seaming rollers, a plurality of cam-slides, one for each seaming-head and a spring or yielding connection between each cam-slide and its 80 seaming-head, and a plurality of ejectors, one for each clamping-disk, substantially as specified.

30. The combination with a carrier having a plurality of reciprocating can-seats, of a plurality of open-ended receivers, a plurality of seaming-heads inside the receivers, each having seaming-rollers and operating-levers therefor, and a cam-slide for actuating said levers, substantially as specified.
